Ralph S. Hauton

UNITED STATES PATENT OFFICE.

PAUL S. HAUTON, OF NEWARK, NEW JERSEY, ASSIGNOR TO HAUTON CORPORATION, OF NEW YORK, N. Y., A CORPORATION OF DELAWARE.

FILLER MECHANISM FOR FOUNTAIN PENS.

Application filed December 22, 1922. Serial No. 608,542.

To all whom it may concern:

Be it known that I, PAUL S. HAUTON, a citizen of the United States, residing in the city of Newark, county of Essex, and State 5 of New Jersey, have invented a certain new and useful Improvement in Filler Mechanism for Fountain Pens, of which the following is a specification, reference being had to the accompanying drawings, which form 10 a part of the same.

An object of my invention is to provide fountain pen filler mechanism operable from the end of a fountain pen opposite to the nib, which may be controlled by turning the 15 same with reference to the barrel of the fountain pen.

Another object of my invention is to positively limit the movement of the filler means.

Another object of my invention is to so 20 construct my filler mechanism as to make it readily removable from a fountain pen for any desirable purpose.

Another object of my invention is the construction of a filler mechanism which may be 25 completely assembled before insertion in the barrel of the fountain pen.

Other objects will be apparent upon reading this specification, taken in connection with the accompanying drawings, in which— 30 Fig. 1 is a longitudinal cross-section of a fountain pen embodying my invention, the ink-bag being shown in normal position;

Fig. 2 is a similar view of a fountain pen with the ink-bag in depressed condition;

Fig. 3 is a cross-section of the presser bar and controlling means;

Fig. 4 is a perspective view of the presser bar support;

Fig. 5 is a cross-section of the filler operating end of the pen with the screw sliding control for the presser bar.

Fig. 6 shows a form of hinge connection between the presser bar arm and presser bar.

Referring now in detail to the drawings: 45 6 represents a fountain pen barrel, 7 a pen nib and 8 the ink-bag. At the filler operating end of the pen, I have provided a turnable button 9 in which is mounted to move integrally therewith the screw 10 having the core 11 and the screw head 12. Adapted to cooperate with the screw 10 and the threaded head 12 is a plug 13 provided with a female thread 15 and having a slot 14. This plug is provided with apertures 16 in register with 50 each other and which are adapted to support

a pin 17 in which is swivelly mounted the presser bar operating lever 18 through the aperture 19 therein. On the presser bar operating lever 18 are two flanges 20, only one of which is shown, having the cam surfaces 60 21 and 22 which fit in the recess 14 of the plug and over the core 11 and between the screw 10 and the head 12. At the desired point the presser bar 23 is connected by a swivelled joint 24 with the presser bar operating lever 18. 65

The turnable button 9 is provided with a recess 26 adapted to cover a portion of the plug 13, said recess having a shoulder 25 which acts as a stop against the plug 13 in 70 its movement toward the same. The part of plug 13 which enters the barrel 6 is preferably provided with serrated surfaces 27 adapted to be held by frictional contact in said barrel, and thereby hold the plug 13 75 in rigid position relative to the turnable button 9.

In operation the filler operating mechanism is assembled so that the turnable button 9, screw 10, core 11, screw head 12, plug 80 13, presser bar operating lever 18 and presser bar 23 constitute one unit, which is adapted to be inserted into the end of a fountain pen barrel in the same manner as a cork is pressed into the mouth of a bottle, the serrated surface 26 of the plug acting to hold the plug in stationary position in the barrel 6. The turnable button 9 is of slightly greater circumference than the rear end of plug 13 which is adapted to fit into said 85 turnable button in a loose enough manner to permit the button to be turned without appreciable friction on the plug. If it is desired to fill the ink-bag 8, the button 9 is turned to cause it and the screw 10 to move 90 away from the stationary plug 13 till the head 12 comes in contact with the cam surfaces 21 of the flanges 20. Further movement of the screw 10 and head 12 connected therewith, will cause the operating lever 18 95 to swivel around the pin 17 till the cam surface 22 of the flange 20 touches the inner end of the slot 14. The presser bar 23 has now completely deflated the ink-bag 8 and further depressing movement of the filling mechanism is stopped by the contact of the flanges 100 20 with the end of slot 14 in plug 13. The ink-bag now being in collapsed condition the opposite end of the pen is then inserted 105 into an ink well and the button 9 is turned 110

into an ink well and the button 9 is turned 110

in the opposite direction till the screw 10 contacts with the cam surfaces 22, thereby raising the presser bar 23 and permitting the ink-bag to expand and thereby draw into itself ink from the well. The turning of the button 9 in the filling direction is limited by the plug 13 coming into contact with the shoulder 25 of the recess 26 in the button 9, which shoulder acts as a stop.

10 I have described what I believe to be the best embodiment of my invention. I do not wish to be limited however, to the embodiment shown, but what I desire to cover by Letters Patent is set forth in the appended 15 claims.

Claims—

1. In a fountain pen embodying an elastic bag and a presser bar adapted to act upon said bag, a turnable head, a screw integrally mounted therein having a circumferentially reduced portion, a presser bar assembly support in screw relation to said screw, said support having a slot therein, a presser bar assembly hingably mounted in said slot and straddling at one end the circumferentially reduced portion of the aforesaid screw and being adapted thereby to positive movement with said screw, and means for limiting the reciprocal movement of said screw.
- 20 2. In a fountain pen embodying an elastic bag and a presser bar adapted to act upon said bag, a turnable head, a screw integrally mounted therein having a circumferentially reduced portion, a presser bar assembly support in screw relation to said screw, said support having a slot therein, a presser bar

assembly hingably mounted in said slot and straddling at one end the circumferentially reduced portion of the aforesaid screw and being adapted thereby to positive movement 40 with said screw.

3. In a fountain pen embodying an elastic bag and a presser bar adapted to act upon said bag, a turnable head, a screw integrally mounted therein having a circumferentially reduced portion, a presser bar assembly support in screw relation to said screw, said support having a slot therein, a presser bar assembly hingably mounted in said slot and straddling at one end the circumferentially 45 reduced portion of the aforesaid screw and being adapted thereby to positive movement 50 with said screw.

4. A presser bar assembly for fountain pens comprising a presser bar, a presser bar arm articulated therewith, a support in which said arm is hingably mounted, a screw having a circumferentially reduced portion and adapted to reciprocal movement to positively control the movement of said 60 presser arm and its articulated presser bar.

5. A presser bar assembly for fountain pens comprising a presser bar, a presser bar arm articulated therewith, a support having a slot therein, said presser bar arm being 65 hingably mounted in said slot, a screw having a circumferentially reduced portion adapted to reciprocal movement to positively control the movement of said presser bar arm.

PAUL S. HAUTON.
